UNITED STATES PATENT OFFICE

HENRY F. SWEET, OF SOUTH BEND, INDIANA

SANITARY BED ATTACHMENT

Application filed February 2, 1931. Serial No. 512,833.

The invention relates to sanitary bed attachments, and has for its object to provide a device which is adapted to be disposed on a bed at the head thereof and between the pillows thereon to prevent two occupants of a bed from breathing into the faces of each other.

A further object is to provide a device of this character adapted to be mounted on a bed in which a plate is mounted on the bed in upright position, said plate carrying a depending bar at one end thereof which extends between the bedding and frame of the bed at the head thereof, said bar carrying means at its lower end and independent of said bed which serves to position said plate in operative upright position on said bed.

A further object is to provide a device of this character adapted to be mounted on a bed and comprising a partition plate carrying means by which it is supported in upright position on said bed without the use of securing means carried by said bed.

A further object is to provide a device of this character forming a vertical partition between the pillows on a bed which may be readily applied thereto and removed therefrom, said device having no fixed connection with said bed.

With the above and other objects in view, the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a perspective view of a bed showing my device mounted thereon in operative position.

Figure 2 is a perspective view of the device.

Figure 3 is a fragmentary vertical section

of a bed showing my device applied thereto.

Figure 4 is a perspective view of a modified form of my device.

Referring to the drawing, the numeral 1 designates the frame of a bed having legs 2 and ends 3, and which frame is adapted to carry a set of springs 4 in any suitable manner. A mattress 5 is mounted on the bed springs and carries the bedding 6. I dispose by sanitary bed attachment between the pillows 7 at the head of the bed. The bed attachment comprises a partition plate 8, which is preferably formed of glass, and which is of a length greater than the width of pillows 7 and of a height to project substantially above said pillows. To one end of plate 8 is secured a channel member 9 receiving the edge of the plate, the upper end of said channel member terminating flush with the upper edge of the plate and its lower end terminating in spaced relation below the lower edge thereof. A horizontal channel member 10 carried by channel member 9 receives the lower edge of the glass plate, said channel members 9 and 10 thus forming a supporting binding for two edges of the plate. A suitable weight 11 is carried by the channel member 9 at the lower end thereof and in spaced relation to the glass plate, said weight preferably being substantially flat and disposed in a plane transverse to the plane of the glass plate for purposes to be hereinafter set forth.

After the bed has been made the plate 8 is placed in the center thereof between the pillows 7 and in upright position with the channel member 9 adjacent the head end of the bed and adapted to extend between the bedding 6 and the bed end 3. When the lower edge of the plate rests on the bedding, the weight 11 will be disposed below the mattress 5 and will serve to maintain the channel 9 and plate 8 in operative upright position without the use of any direct securing or connecting means with the bed. The

weight 11, being flat, readily passes between the bedding and the bed end, and the device is thus easily applied to or removed from the bed when making the bed. The plate 5 forms a vertical partition at the head of the bed extending longitudinally thereof, which is of a height and length sufficient to prevent two occupants of the bed from breathing directly into the faces of each other, and thus 10 prevents the transmission of colds and the like between the occupants of the bed while they are sleeping; the inhalation of the breath of an afflicted person being recognized as one of the most common ways in 15 which persons may be subjected to nasal, pulmonary and other illnesses. It will also be seen that while this device thus deflects the breath of the occupants of the bed, it still permits them to see each other through the 20 glass plate and to talk to each other, so that the feeling of companionship between them is not lost.

In Figure 4 is illustrated a modified form 25 of the device which is also readily attachable to and removable from the bed. In this device a plate 12, similar in size, shape and material to plate 8 of the preferred device, carries a depending arm 13 at one end thereof, said arm 13 being provided with a short 30 forwardly perpendicularly bent portion 14 extending parallel to the lower edge of plate 12. A suitable cross piece 15 is carried by the end of portion 14 and extends perpendicularly to portion 14 and arm 13. In 35 using this device the members 14 and 15 are inserted between the mattress and springs of the bed and the lower edge of the plate 12 rests on the top of the bedding. The cross piece 15 thus holds the plate 12 in operative 40 vertical position by its engagement with the springs and mattress. This embodiment of the invention is easily inserted in or removed from operative position by lifting the end of the mattress sufficiently to permit the device 45 to clear the end of the bed during the manipulation thereof. It will thus be seen that this embodiment of the invention operatively positions the partition on the bed without the use of securing means which connect 50 it to the bed.

While the use of a glass partition plate in both of the illustrated embodiments of the invention is to be preferred, a plate of wood, metal or other suitable material may 55 be employed in place of glass if desired; and in such constructions the use of channel members to bindingly engage the edges of the glass, and frame members such as the horizontal member 10, may be eliminated. The 60 invention is also obviously susceptible of other changes in its specific construction.

The invention having been set forth, what is claimed as new and useful is:

1. A breath shield adapted to be gravitationally supported in a substantially verti-

cal position resting on the bedding of a bed, said shield comprising a bed supported member vertically disposed on the bedding of the bed, a downwardly extending member carried by said bed supported member and terminating below the bed and above a support for the bed and a counterweight carried by said downwardly extending member and forming means whereby said bed supported member is normally maintained in a vertical position on the bedding. 75

2. A breath shield comprising a substantially vertically disposed plate supported on the bedding of a bed adjacent one end thereof, a downwardly extending member carried by said plate and terminating below the bedding and a counterweight carried by said downwardly extending member and entirely supported thereby, said counterweight forming means whereby said vertically disposed plate is normally maintained in a vertical position on the bedding. 85

In testimony whereof I affix my signature.

HENRY F. SWEET.
